(57) **CLAIM**

The ornamental design for a compact mobile C arm system, as shown and described.

DESCRIPTION

FIG. 1 is a front right perspective view of a compact mobile C arm system with a first environmental structure according to the present invention.

FIG. 2 is a left side view of the compact mobile C arm system of FIG. 1.

FIG. 3 is a right side view of the compact mobile C arm system of FIG. 1.

FIG. 4 is a front view of the compact mobile C arm system of FIG. 1.

FIG. 5 is a rear view of the compact mobile C arm system of FIG. 1.

FIG. 6 is a top view of the compact mobile C arm system of FIG. 1.

FIG. 7 is a bottom view of the compact mobile C arm system of FIG. 1.

FIG. 8 is a front right perspective view of the compact mobile C arm system with a second environmental structure.

FIG. 9 is a left side view of the compact mobile C arm system of FIG. 8.

FIG. 10 is a right side view of the compact mobile C arm system of FIG. 8.

FIG. 11 is a front view of the compact mobile C arm system of FIG. 8.

FIG. 12 is a rear view of the compact mobile C arm system of FIG. 8.

FIG. 13 is a top view of the compact mobile C arm system of FIG. 8; and,

FIG. 14 is a bottom view of the compact mobile C arm system of FIG. 8.

The broken lines in FIGS. 1-14 are included for the purpose of illustrating environmental structure and form no part of the claimed design.

1 Claim, 14 Drawing Sheets
